UNITED STATES PATENT OFFICE.

JOHN A. SMITH, OF HARRISBURG, PENNSYLVANIA, ASSIGNOR TO ELLIOTT-FISHER COMPANY, OF HARRISBURG, PENNSYLVANIA, A CORPORATION OF DELAWARE.

COMBINED KEY-CONNECTING AND RIBBON-SHIFTING MECHANISM FOR COMBINED TYPE-WRITERS AND ADDERS.

1,228,492.

Specification of Letters Patent. Patented June 5, 1917.

Application filed June 26, 1909. Serial No. 504,501.

To all whom it may concern:

Be it known that I, JOHN A. SMITH, a citizen of the United States of America, residing at Harrisburg, in the county of Dauphin and State of Pennsylvania, have invented certain new and useful Improvements in Combined Key-Connecting and Ribbon-Shifting Mechanism for Combined Type-Writers and Adders, of which the following is a specification.

My present invention relates to combined key connecting and ribbon shifting mechanism for combined typewriting and adding machines.

The object of the invention is to establish an interdependent relation between the mechanism which controls the operation of the adder and the mechanism which controls or determines the color in which the matter printed or recorded shall be displayed, to the end that different colors may be appropriated to different classes of work, as for instance one color for numbers recorded and added and a contrasting color for numbers recorded but not added, as for instance the total of a column, with positive assurance that the matter recorded will appear in the proper color.

In the accompanying drawings—

Figure 1 is a perspective view of a portion of an Elliott-Fisher writing-adding machine equipped in accordance with my invention, the parts being shown in the positions they occupy when the machine is set for both printing and adding.

Fig. 2 is a similar view with certain of the parts occupying different positions to permit the use of a different stripe or track of the ribbon while printing and adding.

Fig. 3 is still another view of this character with the parts in the positions they occupy for recording in a distinctive color without adding, and

Fig. 4 is a vertical sectional view through the machine.

Each part is indicated by its appropriate reference character throughout the views.

The Elliott-Fisher billing-adding machine.

The Elliott-Fisher billing-adding machine to which my invention is shown ap-

plied is what is known as a flat platen or downwardly printing typewriter equipped with adding mechanism. The typewriting machine includes a flat platen 1 over which a machine frame 2 travels longitudinally for line spacing. Mounted to travel transversely of the platen on the frame 2 for letter spacing is a carriage 3 which supports downwardly acting numeral printing mechanism 4 operated from keys 5. The carriage 3 is propelled in the direction of letter spacing by propelling mechanism not shown and is controlled by an escapement 6 operated from the keys 5 to permit a step-by-step advance of the carriage. For a more complete disclosure of the machine than is considered necessary at this time, reference is made to Patent No. 573,868 to R. J. Fisher.

70

The adding mechanism.

The adding mechanism is an ordinary adjunct of the Elliott-Fisher machine of commerce and is fully disclosed in Patents No. 825,494 to John A. Smith, No. 829,971 to Laganke and Smith, and in the copending application of Laganke and Smith No. 308,279. It will suffice, therefore, for present purposes to mention that the register or adding mechanism proper 7 is adjustably mounted on a horizontal register supporting bar 8 carried by suitable brackets extending in rear of and supported by the main frame 2 of the machine. The register 7, which is thus adapted to be positioned for the addition of numbers printed in a column at any point on the work sheet, includes a series of denominational members or number wheels 9, indicated in dotted lines in Fig. 4 and corresponding to the denominational orders of the column. With these number wheels is associated carrying mechanism, not shown, but well understood in the art. The number wheels 9 are designed to be operated by a master wheel or actuator 10 mounted on the carriage and presented, by the movement thereof, into co-operative relation with successive number wheels from higher to lower order as the printing point of the typewriter moves from higher to lower order across the column on the work sheet.

The master wheel 10 is operated from the

keys 5 of the typewriter through suitable operating connections each of which imparts to the master wheel a rotary movement corresponding in degree to the value of the particular key operated. One of these operating connections is shown generally in Fig. 4 and will be seen to include a lever 11 geared to the master wheel shaft 12 and operated by a lever 13 fulcrumed at its rear end, as shown at 14, and provided at its front end with a depending link 15 adapted to swing back and forth. This movement of the link 15 causes a lug 16 thereon to engage or disengage a notched pin 17 projecting from the stem 18 of the adjacent key 5. For the purpose of swinging all of the links 15 forward to engage the same with the keys 5, an oscillatory key-connecting-yoke 19 is mounted in the carriage casing, the front bar 20 of said yoke being received within longitudinal slots 21 in the links 15.

The key connecting mechanism.

In the Elliott-Fisher machine of commerce provision is made for automatically swinging the links 15 into engagement with the numeral keys 5 whenever, in the travel of the carriage, the printing point of the machine moves into the column or adding field and the master actuator 10 moves opposite the register, the numeral keys being unburdened at other times or in other positions of the carriage to facilitate the printing of digits outside of the adding field. The automatic key connecting mechanism here shown is generally identical with that found in the specified machine and disclosed in Patent No. 863,232 to John A. Smith.

Within the casing 3 is mounted a yoke-operating lever 22 having its front end in engagement with the bar 20 of the key connecting yoke 19. At the rear end of the lever 22 is mounted an abutment roller 23 shiftable into and out of coactive relation with the front end of a secondary lever 24, the rear extremity of which extends through the rear wall of the casing and is co-operatively related to what is known as the key connecting arm 25 having a cam which, upon the forward movement of the carriage, rides under a ledge or plate 26 extended from the lower front corner of the register 7. When the arm 25 is depressed by the register plate 26 the lever 24 is swung and by engagement with the abutment roller 23 swings the key connecting lever 22 which in turn swings the yoke 19 to shift all of the links 15 into engagement with the adjacent key stems, thus effecting automatically an operative connection between the normally disconnected keys and the adding mechanism, which connection is likewise automatically broken when the arm 25 passes from under the ledge 26 at the same time the master wheel is passing out of the reg-

ister and the printing point of the typewriter is passing beyond the column.

This automatic key connecting mechanism is variable, that is to say, it is capable of being set for automatic operation or unset to prevent the keys from being connected when the printing point of the typewriter moves opposite the column. In the Smith patent, to which reference has been made, this control of the key connection is effected by means of a key, usually referred to as the total key, 27, exposed above the carriage 3 at the left hand end thereof, as shown in Fig. 1, for instance, and connected as by a lever 28 with an abutment plate 29 shiftable on the lever 22 and carrying the roller 23.

In the forward position of the key 27, shown in Fig. 1, the roller 23 is positioned above the rear end of the lever 24, as shown in Fig. 4. This is what is known as the "add" position of the total key because in this position the automatic key-connecting mechanism is set for operation so that when the master wheel moves opposite the register, the keys will be connected to permit the operation of the adder. When the key 27 is moved back to the position shown in Fig. 3 for instance, the lever 28 will be swung to shift the roller 23 forward beyond the end of the lever 24. This is what is generally known as the "total" position of the parts because the operative connection between the levers 22 and 24 is now broken and as a consequence the keys will not be connected with the adding mechanism when the printing point moves into the column and the total will therefore be printed at the foot of the column without operating the register upon which the total value of the column of numbers is displayed.

The entire mechanism described under the last heading is shown in the identified Smith patent, to which reference is made for a more specific disclosure of the parts.

The ribbon mechanism.

The ribbon mechanism of the Elliott-Fisher machine is disclosed in Patents No. 723,884 to Laganke and Smith and No. 723,936 to John A. Smith. For the purposes of the present disclosure it is sufficient to say that this ribbon mechanism includes two spool shafts 30 located at the sides of the carriage and carrying ribbon spools 31 shiftable longitudinally of the shafts 30 and connected by a ribbon guiding frame 32. The shafts 30 are rotated by mechanism, not shown, to feed the ribbon 33 endwise from one spool to the other as the carriage advances.

The ribbon ordinarily utilized and that shown in the drawing has longitudinal stripes of contrasting colors as for instance a narrow red stripe 34 at the rear edge of

the ribbon and a very much wider black stripe 35. The ribbon spools, together with the ribbon and the connecting frame 32, are shifted rearwardly to expose the writing by means of a ribbon shifting key 36 formed at one end of a ribbon shifting lever 37 suitably mounted on the carriage and connected to the frame 32, see Fig. 1. As the ribbon is of sufficient width to present a number of printing tracks four of which are black and one red, a stop plate 38 is mounted on the carriage casing and is adjustable to arrest the ribbon shifting lever 37 at any one of several points corresponding to the tracks of the ribbon.

An indicator 39 is associated with the plate 38 to aid in the adjustment thereof and to indicate the particular track of the ribbon which will be presented at the printing point upon the return of the lever 37 after the key 36 has been pressed down to shift the ribbon away from the line of writing. The stop plate 38 is provided with a key or finger piece 40 by which it may be manipulated, but it may be remarked in passing that while the plate 38 constitutes a stop limiting the return of the ribbon when the latter has been shifted back from the line of writing, it also constitutes a ribbon shifting member, since it will be obvious that the operator, by pushing the key 40 forward from the position shown in either Fig. 2 or Fig. 3, will not only adjust the plate 38, but will cause the latter to swing the lever 37 and thus shift the ribbon to present at the printing point that particular printing track which is indicated by the position of the plate. The lever 37 is held against the stop 38 by a ribbon retracting spring 41 which yieldingly retains the ribbon in the position determined by the stop 38.

The connection between the key connecting and the ribbon shifting mechanisms.

It has been stated that one object of my present invention is to insure the printing of certain classes of matter in appropriate colors. For instance it is customary to print in black all numbers which are recorded in the column or adding field and also added in the register and to print in red, or other contrasting color, the total or other matter printed in the column, but not added. Heretofore it has been possible to print in either color numbers which are both printed and added or which are printed only. This is objectionable because it has made it impossible to determine from the record itself whether or not the printed numbers have been included in the computation and because of the possibility of printing the total in the same color as the numbers in the column in case the operator failed to shift the ribbon to present the red or contrasting color

stripe to the printing point. These objections are overcome and the object of the invention attained by effecting a connection between the total key 27 of the key connecting mechanism and the stop 38 of the ribbon shifting mechanism, the connection being such that whenever the stop plate 38 is moved to proper position to allow the red stripe of the ribbon to be presented at the printing point the total key will necessarily be shifted to its unset or total position, whereas when the stop plate 38 of the ribbon mechanism is shifted away from the red position the total key will be likewise shifted to its set position.

To effect the desired connection I fulcrum upon the left hand end of the carriage casting at 42, see Fig. 1, a total key shifting lever 43 having its upper end disposed at an angle and bifurcated, as shown at 44, to engage the key 27. The opposite or lower end of the lever 43 is connected by a link 45 to a bell crank lever 46 the opposite arm of which is bifurcated, as indicated at 47, to engage a pin 48 which may be integral with the plate 38, but is shown carried by the rear end of an arm 49 secured to said plate. This character of connection between the plate 38 and the lever 46 enables the plate to have independent movement between certain limits in order that it may be shifted to position any one of the several printing tracks of the black stripe of the ribbon opposite the printing point without affecting the key connecting mechanism, but whenever the key 40 is operated to throw the stop plate 38 back to the red position, the pin 48 will be engaged within the bifurcation 47 and positively swing the levers 46 and 43 to shift the total or setting key 27 of the key connecting mechanism to its total or unset position.

Operation.

In order that the operation of the mechanism may be better understood, attention is directed first to Fig. 1. In this figure the key 27 is shown at "add" in which position the roller 23 will be located above the lever 24, as shown in Fig. 4, which is its set position. When the key 27 is in this position the keys 5 will be operatively connected with the adding mechanism 7 whenever the printing point of the typewriter moves into the column. It will also be noted that the key 40 and plate 38 are in their extreme forward positions in Fig. 1 and that the extreme forward printing track of the ribbon is opposite the printing point. If now, the key 40 of the stop plate 38 is shifted back to any one of the three positions immediately in rear thereof, see for instance Fig. 2, the ribbon will be allowed to move forward to present any one of the remaining tracks of the black stripe of the ribbon opposite the printing point. If, however, the key 40 is thrown

to its extreme rearward or "red" position, shown in Fig. 3, the lever 46 will be operated to swing the lever 43 and the key 27 rearwardly to the total position in which the roller 23 will be withdrawn from over the end of the lever 24 so that when the printing point of the typewriter moves into the adding field with the red track of the ribbon opposite the printing point, the key-connecting mechanism will not operate to connect the keys with the adder. Consequently, if a number appears in red in the adding field, it will be evident that such number has not been included in the computation effected by the adding mechanism. As soon, however, as the key 40 is moved away from the red position the setting key 27 of the key connecting mechanism will be moved to "add" or set position, so that if a number printed in the column appears in black it will be equally evident that such number has been included in the computation effected by the adding mechanism.

In conclusion, attention is directed to the fact that the key connecting mechanism which enters into the combination embraced by my invention is operated automatically by the movement of the typewriter carriage and that it is set for automatic action and unset for non-action by the act of manipulating the ribbon mechanism to select or determine the color in which the record shall appear, the key 40 constituting a ribbon shifting member which is movable to determine or select the color of the record and also to determine whether the keys shall be connected to or disconnected from the adding mechanism when the printing point of the typewriter is opposite the adding field.

It is thought that from the foregoing, the construction and operation of the mechanism comprehended in my invention will be clearly understood, but I wish to expressly reserve the right to effect such variations of the illustrated structure as may come fairly within the scope of the protection prayed.

What I claim is:—

1. The combination with recording mechanism and keys, of adding mechanism, automatically operated key connecting mechanism, operative to connect the adding mechanism and keys, and including setting means, multicolor inking means movable to determine the color of the record, and means adjustable with the setting means to determine the position of the inking means.
2. The combination with recording mechanism and keys, of adding mechanism, automatically operated key connecting mechanism, intermediate of the adding mechanism and keys, and including setting means, multicolor inking means movable to determine the color of the record, and a stop adjustable with the setting means and coacting with the inking means.

3. The combination with recording mechanism and keys, of adding mechanism, key connecting mechanism including setting means, operative to control the subsequent operation of the key connecting mechanism to connect the adding mechanism and keys, a laterally shiftable multicolor ribbon for the recording mechanism, and means adjustable with the setting means to determine the position of the ribbon.

4. The combination with recording mechanism and keys, of adding mechanism, key connecting mechanism, adapted to connect the keys and adding mechanism, and including setting means, a laterally shiftable multicolor ribbon for the recording mechanism, and a stop co-operatively related to the setting means and disposed to limit the movement of the ribbon in one direction.

5. The combination with recording mechanism and keys, of adding mechanism, key connecting mechanism, arranged to connect the keys and adding mechanism, and including setting means, which may be set prior to the connection of the keys and adding mechanism, a laterally shiftable multicolor ribbon for the recording mechanism, a member movable to shift the ribbon laterally, and an operative connection between said member and the setting means.

6. The combination with a traveling carriage, recording mechanism, and keys, of adding mechanism, key connecting mechanism operated by the movement of the carriage to cause the connection of the keys and adding mechanism and including setting means movable to determine whether or not the movement of the carriage shall effect such connection of the keys, and multicolor inking means co-operatively related to the setting means of the key connecting mechanism.

7. The combination with a traveling carriage, recording mechanism, and keys, of adding mechanism, key connecting mechanism operated by the movement of the carriage to cause the connection of the keys and adding mechanism and including setting means movable to determine whether or not the movement of the carriage shall effect such connection of the keys, multicolor inking means, color selecting mechanism, and a connection between the color selecting mechanism and the setting means.

8. The combination with a traveling carriage, recording mechanism, and keys, of adding mechanism, key connecting mechanism operated by the movement of the carriage to cause the connection of the keys and adding mechanism and including setting means movable to determine whether or not the movement of the carriage shall effect such connection of the keys, a laterally shiftable multicolor ribbon, and means for determining the position of the ribbon, said

last named means being coöperatively related to the setting means of the key connecting mechanism.

9. The combination with a traveling carriage, recording mechanism, and keys, of adding mechanism, key connecting mechanism operated by the movement of the carriage to cause the connection of the keys and adding mechanism and including setting means movable to determine whether or not the movement of the carriage shall effect such connection of the keys, a laterally shiftable multicolor ribbon, and a key operative to shift the ribbon and controlling the setting means of the key connecting mechanism.

10. The combination with a traveling carriage, recording mechanism, and keys, of adding mechanism, key connecting mechanism operated by the movement of the carriage to cause the connection of the keys and adding mechanism and including setting means movable to determine whether or not the movement of the carriage shall effect such connection of the keys, multicolor inking means, and a single key controlling the setting means and movable to determine the color of the record.

11. The combination with a traveling carriage, recording mechanism, and keys, of adding mechanism, key connecting mechanism operated by the movement of the carriage to cause the connection of the keys and adding mechanism and including setting means movable to determine whether or not the movement of the carriage shall effect such connection of the keys, a multicolor ribbon, color selecting means adjustable to determine the position of the ribbon, and an operating key common to both the color selecting means and the setting means.

12. In a combined typewriting and adding machine, the combination with a typewriter including a carriage, keys and printing mechanism, of a register, operating connections therefor, key connecting mechanism operated by the movement of the carriage to connect the keys and said operating connections of the register, said key connecting mechanism including setting means movable to render the key connecting mechanism operative or inoperative, a multicolor ribbon for the printing mechanism, and mechanism for insuring a given position of the setting mechanism when the ribbon is in a given position.

13. In a writing adding machine, a carriage, keys, printing mechanism and an adding mechanism or register, of key connecting mechanism serving in a given position to operatively connect the keys and adding mechanism and including a total key, a ribbon mechanism including means for shifting the ribbon to present different stripes or tracks thereof to the printing point of the

machine and a movable stop coöperating with said shifting means to determine the writing position of the ribbon, and a connection between the total key and ribbon stop.

14. The combination with recording mechanism and keys, of adding mechanism, key connecting mechanism operative to establish a coöperative relation between the keys and the adding mechanism and including setting means, multicolor printing mechanism, a key movable to select or determine the color of the record, and a connection between said key and the setting mechanism, said connection including a bell crank lever, means connecting said lever with the setting mechanism, and a device movable with the key and arranged to engage and operate the bell crank lever during a portion only of the movement of said key.

15. The combination with recording mechanism and keys, of adding mechanism, key connecting mechanism, automatically movable into position to connect the keys and adding mechanism, and including setting means movable to set and unset position to control the subsequent movement of the key connecting mechanism, multicolor inking means for the printing mechanism, and means for securing an interdependent relation between the setting means of the key connecting mechanism and the multicolor inking means whereby contrasting colors will be printed when the setting means is in different positions.

16. In a computing typewriter, the combination with a carriage, keys and printing mechanism, of a computing device, actuating means whereby the computing device may be placed under the control of the keys, variable key connecting mechanism adapted to be automatically operated when the carriage moves into the adding field to place the computing device under the control of the keys, setting means operative to vary the key connecting mechanism to determine whether the computing device shall be placed under the control of the keys when the adding field is reached, a multicolor ribbon and means controlling the setting means and operative to shift the ribbon.

17. In a combined typewriting and adding machine, the combination with a typewriter including a carriage, keys and printing mechanism, of a register, operating connections therefor, key connecting mechanism operated to connect the keys and said operating connections, ribbon mechanism including means for shifting the ribbon laterally, an adjustable stop device for the ribbon shifting means and operative connection between said stop device and the key connecting mechanism.

18. In a combined typewriting and adding machine, the combination with a type-

- writer including a carriage, keys and printing mechanism, of a register, operating connections therefor, key connecting mechanism operative to connect the keys and said 5 operating connections, ribbon mechanism including a device for shifting the ribbon and an adjustable stop for said shifting device, the shifting device being movable independently of the stop to displace the ribbon from 10 the printing point, and a connection between the stop device and the key connecting mechanism.
19. In a combined typewriting and adding machine, the combination with a typewriter including a carriage, keys and printing mechanism, of a register, operating connections therefor, key connecting mechanism operative to connect the keys and the operating 15 connections, ribbon mechanism including a ribbon shifting device, an adjustable stop member coacting therewith, and connections between said adjustable stop member and the key connecting mechanism, said connections permitting independent 20 movement of the stop device to certain positions but effecting an operative relation between said stop device and the key connecting mechanism during the movement of the stop device to certain other positions.
- 25 20. In a combined typewriting and adding machine, the combination with a typewriter including a carriage, keys and printing mechanism, of a register, operating connections therefor, key connecting mechanism operated by the movement of the carriage to 30 connect the keys and said operating connections, said key connecting mechanism including setting means movable to render the key connecting mechanism operative or 35 inoperative, ribbon mechanism including a shifting device for the ribbon 40 and an adjustable stop member for the shifting device and a connection between said stop member and the setting means of the key connecting mechanism. 45
21. In a combined typewriting and adding machine, the combination with a typewriter including a carriage, keys and printing mechanism, of a register, operating connections therefor, key connecting mechanism operated by the movement of the carriage to 50 connect the keys and said operating connections, said key connecting mechanism including setting means movable to render the key connecting mechanism operative or 55 inoperative, ribbon mechanism including a shifting device for the ribbon and an adjustable stop member for the shifting device, and a connection between said stop member and the setting means of the key connecting mechanism, said connection including means whereby said stop member may be moved to certain positions independently of the setting means. 60
22. In a writing-adding machine, a carriage, keys, printing mechanism, adding mechanism, key connecting mechanism operated by the movement of the carriage to 65 place the adding mechanism under the control of the keys and including a total key movable to determine whether the key connecting mechanism shall be operated as stated, a ribbon mechanism including ribbon shifting means and a movable stop coacting with the shifting means, and a connection between the total key and said stop. 70
- In testimony whereof I affix my signature in presence of two witnesses.
